UNITED STATES PATENT OFFICE.

ROBERT MALZAHN, OF WEST BEND, WISCONSIN.

POCKETBOOK.

Application filed May 2, 1922. Serial No. 557,829.

To all whom it may concern:

Be it known that I, ROBERT MALZAHN, a citizen of the United States, and resident of West Bend, in the county of Washington

5 and State of Wisconsin, have invented certain new and useful Improvements in Pocketbooks; and I do hereby declare that the following is a full, clear, and exact description thereof.

10 The invention relates to pocket-books of a type in which bills are conveniently folded.

Difficulty has been experienced hitherto with bill folds by reason of the fact that 15 when the fold is opened for the removal of a bill, the entire contents are exposed. This involves a serious disadvantage, since it is oftentimes desirable to conceal money of large amounts for various reasons.

20 The invention comprises a cover, a major outer fold member secured to the cover and forming a pocket for the reception of bills of large denomination, and a major inner fold member stitched to said outer fold

25 member and forming a pocket for the reception of bills of smaller denomination. The ends of the bills are adapted to be folded over as the pockets are not long enough to receive an entire bill. Flaps are

30 provided for covering the ends of the bills.

A primary object of the invention is the provision of means adapted to conceal part 35 of the contents, one of the pockets remaining invisible, while the other is being opened, and yet to permit ready access to the bills and the removal thereof from either pocket. To extract a bill the pocket-book is merely 40 opened and the flap bent backwardly to expose the ends of the bills which may be withdrawn by the hand.

The invention has as a secondary object, a compact and neat arrangement of parts. As the pockets are not of bill length, the fold is not long and the pocket-book has 45 only one line of fold, so that its dimensions are such as to adapt it for ready reception in a pocket. As there is only one line of fold, the resulting arrangement, after folding is comparatively thin so that there is no bulging.

50 With the above and other objects in view, which will appear as the description proceeds, my invention resides in the novel construction, combination and arrangement of parts, substantially as hereinafter described and more particularly defined by the ap-

pended claims, it being understood that such changes in the precise embodiment of the herein disclosed invention may be made as come within the scope of the claims. 60

In the accompanying drawing, I have illustrated one complete example of the physical embodiment of the present invention constructed according to the best mode I have so far devised for the practical application of the principles thereof, and in which:—

Figure 1 is a plan of the inside of the inside of the invention with flaps bent backwardly and parts broken away to reveal the 70 entire structure.

Figure 2 is a side view with fold members bent to reveal the pockets.

Figure 3 is a cross section on the line 3—3 of Figure 2.

Figure 4 is a view of the pocket-book closed.

Figure 5 is a view of various pieces in separated relation.

Cover 10 is provided with a post 11 and 80 a socket 12 adapted to receive the post. For convenience in description, the end on the left in the Figures 1 and 2 will be referred to as the left end; the other end is the right end. 85

An outer fold member 13 is secured along line 14 at the right end edge of cover 10. Flap 15 is, also, secured along this line. Outer fold member 13 is, also, secured along the side of cover 10 by row of stitching 16. 90 Two sides of the outer fold member are unsecured so that a pocket 17 is formed between the outer fold member and cover 10. Inner fold member 18 is secured to the outer fold member 13 by row of stitching 19 and 95 by row 20. Row 20 cooperates, also, with rows of stitching 21—21' to secure pocket member 22 in position. Inner fold member 18 being free along two edges forms a pocket 23 with outer fold member 13. 100

Pocket member 22 forms also a pocket with inner fold member 18, the pocket being adapted to receive cards, etc. Pockets 17 and 23 are somewhat shorter than the length of a bill. Bills of smaller denomination are 105 placed in pocket 17 with their ends projecting at the left. A flap 24 is secured by row of stitching 25 and is adapted to cover the folded ends of the bills. Pocket 23 receives bills of larger denomination which 110 are folded at the right end, the ends being covered by flap 15.

2
 Pocket member 26 is secured to inner fold member 18 by rows of stitching 27, 28, and 28'. The pocket-book is designed to be folded on a line midway between pocket members 26 and 22 and socket 12 cooperates with post 11 to maintain parts in closed position. When it is desired to remove a bill, end 29 of cover 10 is released from post 11 and the pocket-book is unfolded. The bills 10 remain invisible, however, flaps 15 and 24 normally lying flat.

If it is desired to remove a bill of small denomination, flap 24 is moved upwardly, exposing the ends of the bills. On the re- 15 moval of any desired number, the flap is permitted to assume normal lowered position and the pocket-book may be closed. In such an operation the bills contained in pocket 17 remain concealed. Obviously, if 20 it is desired to remove a bill from pocket 17, flap 15 may be merely moved upwardly. In either case, the quantity of money in the pocket-book cannot be determined by an ob- 25 server. When the bill-fold has been opened, the cards, or other articles, retained by minor pocket members 22 and 26 may be readily removed. The pocket-book, as an 30 entirety, folds only on the line intermediate between minor pocket members 22 and 26. Consequently, there are only two thicknesses involved and the resulting arrangement is compact and well adapted to the dimensions of a pocket.

I claim:—

35 1. The combination of an elongated, flexible member, a rectangular flexible member having two adjacent sides secured to said first mentioned member, and a second rectangular member having a pair of adjacent

sides secured to said first mentioned rec- 40 tangular member along the free edges of said first mentioned rectangular member.

2. The combination of an elongated, flexible member, a rectangular flexible member secured to said first mentioned member along two adjacent sides of said second mentioned member, two adjacent sides of said second mentioned member being free, 45 a third flexible member secured along two adjacent sides to said second flexible member, said third flexible member being rectangular and having two adjacent free sides, 50 said third flexible member and said second flexible member forming a pocket and said second flexible member cooperating with said first flexible member to form an additional pocket, and a pair of oppositely disposed flaps secured along one edge of each thereof and adapted to overlap the ends of 55 said pockets.

3. The combination of an elongated, flexible member, an outer fold member secured thereto along two adjacent edges of said fold member, an inner fold member secured to said outer fold member along two free 60 edges of said outer fold member, a pair of flaps, each having an edge secured to said first mentioned flexible member adapted to overlap the ends of said fold members, a post carried by said first mentioned flexible 65 member, and a socket carried by first mentioned flexible member adapted to receive 70 said post.

In testimony that I claim the foregoing I have hereunto set my hand at West Bend, 75 in the county of Washington and State of Wisconsin.

ROBERT MALZAHN.
